VENTILATOR

James H. McDerment, Cleveland, Ohio, assignor
to The Swartwout Company, Cleveland, Ohio,
a corporation of Ohio

Application August 21, 1935, Serial No. 37,195

2 Claims. (Cl. 98—42)

This invention relates to a ventilator and has particular reference to the damper and damper operating means for use in such ventilator. While I have illustrated and described a ridge ventilator, it is to be understood that the damper and operating means may be used in ventilators of other types.

The object of the invention, broadly stated, is to provide improved damper suspension and operating mechanism, to produce a simple and durable construction which is less likely to get out of order and which may be operated from a remote position. A more limited object is to provide for a suspension of the damper on flexible elements and to provide a sliding actuator adapted for motion parallel to the damper to cause movement of the damper transversely to itself. A still further object is to provide actuating means for the sliding bar actuator possessing a high mechanical advantage and remote controlled means for operating such actuating means.

With the foregoing and other and more limited objects in view, as will become apparent, the invention consists in the novel features of construction and arrangements of parts hereinafter described and illustrated in the accompanying drawings in which Fig. 1 is a transverse section corresponding substantially to the line 1—1 of Fig. 2; Figs. 2 and 2a are a fragmentary longitudinal vertical section taken substantially centrally of Fig. 1; Figs. 3 and 3a are a horizontal section showing the operating mechanism in elevation; Fig. 4 is a detail section of the mounting of the threaded operating mechanism; Fig. 5 is a fragmentary vertical section similar to Fig. 2 and showing a modified form; Fig. 6 is a horizontal section similar to Fig. 3 and corresponding to the modified form of Fig. 5 and Figs. 7 and 8 are detail sections taken on the lines 7—7 and 8—8, respectively, of Fig. 6.

Referring now to Fig. 1, it will be seen that I have illustrated my invention as applied to a building having roof elements 10 spaced apart to form an opening 11 adapted to be controlled. Secured to the elements 10 are sheet metal elements 12 converging upwardly and terminating in vertical, downturned edges 13. Spanning the space between the edges 13 and secured to the elements 12 are a plurality of spaced connectors 14 which are also secured to bow elements 15 which extend above the elements 12 and have connecting portions 16 forming mounting means for the operating mechanism. The lower ends 55 of the elements 15 are turned up as indicated

at 17 and receive the lower edges of baffle elements 18. Secured to the corners of the elements 15 are supports 19 between which and the element 15 is clamped a ridge roll 20. The supports 19 connect with the upper edges of the elements 18 to hold the same in position. A damper 21 is shown in position to close the opening defined between the edges 13. This damper is moved vertically by flexible elements 22 connected thereto at spaced positions by means of suitable brackets 23. The elements 22 pass upwardly and over sheaves 24 which are mounted by means of suitable brackets on elements 16. Flexible elements 22 pass longitudinally over additional sheaves 25 carried on other of the elements 16. From the sheaves 25 the flexible elements 22 pass to suitable connections 26 carried by a sliding actuator 27. It will thus be clear that by longitudinal movement of the actuator 27 it will be possible to raise and lower the damper 21 vertically. Additional means are provided for reciprocating the actuator 27 and for holding the same in a fixed position when it is desired to hold the damper open.

In the form of my invention shown in Figs. 1 to 4 inclusive, the actuating means for the sliding actuator 27 consists of a threaded element 28 secured to such actuator by means of a pivotal connection as indicated at 29 to a transverse member 30 which connects the spaced elements making up the sliding actuator 27. The threaded element 28 is received in an internally threaded sleeve 31 which is provided with internal shoulders at each end, one receiving a bearing sleeve 32 mounted in a fixed journal 33 while the other receives an extended tubular element 34. The element 34 is connected at its other end to a shaft 35 which is mounted in a suitable journal 36 and held against longitudinal motion by a nut 37. A sprocket wheel 38 is mounted on the shaft 35 and provided with a chain 39 extending downwardly to a convenient operating position. It will be obvious that the use of the threaded actuating mechanism will result in a construction which will cause the actuator 27 to remain in any position and that no latch mechanism other than the threaded actuator is necessary. The spacing of the two elements making up the actuator 27 and the attachment of the flexible elements 22 to each thereof will result in maintaining the damper at all times in a level position and will prevent tipping.

In Figs. 5 to 8 inclusive, I have shown a modified form of the invention, differing from the embodiment described above in that there is con-

nected to the slidable actuator 27 a flexible element 40 which is passed around a stationary sheave 41 and back to a sheave 42 carried by a suitable bracket 43 mounted on a transverse member 44 connected to the two parts of the slid-
5 able actuator 27. From the sheave 42 the flexi-
ble element 40 passes to a winding drum or shaft
45 which is rotatably mounted in suitable brackets
46 carried by the spaced frame elements 47. The
10 shaft 45 carries a sprocket wheel 48 upon which is
received a sprocket chain 49 extending down-
wardly to a convenient operating position. In
this form of the invention, a latch must be pro-
vided for holding the actuator 27 in position to
15 hold the damper 21 open. This latch may take
the form of a pivoted latch element 50 carried
by a transverse member 51 connected to the actu-
ator 27 and a latch receiving element 52 fixedly
20 carried by a transverse member 53 mounted on
the framework 47. The latch element 52 is made
up of spaced plates provided with vertical and
angular slots 54 and 55 having movable pins 56
25 and 57 received therein. When the latch element
50 enters the latch receiving element 52, a notch
58 in the element 50 engages the pin 57 which
rides up the cam slot 55 and causes the notch 59
30 to interlock with the pin 56. Upon release of the
actuator, causing slight motion of the member 50
to the left, the pin 57 is released whereby, upon
slight motion to the right, the element 50 may be
35 released from the pin 56 for restoration of the
parts to the position shown in Fig. 5.

From the foregoing it will be clear that I have provided a device which is well adapted for its intended purpose and while I have shown and described the present preferred embodiments I wish it understood that I am not limited to the details of the disclosure but only in accordance with the appended claims and the prior art.

40 Having thus described my invention, what I claim is:

1. In a ventilator, in combination with means defining a horizontal opening to be closed, a horizontally disposed damper and means for moving said damper vertically, parallel to itself, to and from closing relation to said opening, said last means comprising pulleys fixed with respect to said first means, one of said pulleys being spaced

from another thereof laterally of said damper and one of said pulleys being spaced from another thereof longitudinally of said damper whereby the vertical projections of lines extending from each pulley to all the others will outline an area on said damper, flexible elements passing over said pulleys and extending vertically downwardly and connected to said damper whereby to suspend the same, an actuating element mounted for reciprocating movement longitudinally of said damper, said flexible elements being connected to said actuating element, remote control means for operating said actuating element and connecting means interposed between said actuating means and said remote control means and including mechanism for securing a mechanical advantage. 5

2. In a ventilator, in combination with means defining a horizontal opening to be closed, a horizontally disposed damper and means for moving said damper vertically, parallel to itself, to and from closing relation to said opening, said last means comprising pulleys fixed with respect to said first means, one of said pulleys being spaced from another thereof laterally of said damper and one of said pulleys being spaced from another thereof longitudinally of said damper whereby the vertical projections of lines extending from each pulley to all the others will outline an area on said damper, flexible elements passing over said pulleys and extending vertically down- 20
25

35
wardly and connected to said damper whereby to suspend the same, an actuating element mounted for reciprocating movement longitudinally of said damper, said flexible elements being connected to said actuating element, remote control means for operating said actuating element and connecting means interposed between said actuating means and said remote control means and including a threaded element connected to said actuator, a second threaded element thread- 40
45
edly engaging said first element and mounted for rotation but constrained against longitudinal motion for operating said actuator, said second threaded element receiving said first threaded element and having a sleeve portion surrounding the latter, and fixed journal means receiving said sleeve portion.

JAMES H. McDERMINT.
